UNITED STATES PATENT OFFICE.

ALEXANDER HAY, OF PHILADELPHIA, PENNSYLVANIA.

SHOE AND GAITER.

Specification of Letters Patent No. 26,493, dated December 20, 1859.

To all whom it may concern:

Be it known that I, ALEXANDER HAY, of the city of Philadelphia and State of Pennsylvania, have invented a new and Improved Mode of Making Shoes and Gaiters so as to Dispense with Strings in Securing Them on the Feet; and I do declare the following is an exact description thereof, reference being had to the accompanying drawings and letters of reference marked thereon.

In order to show distinctly the nature of my improvement, it is necessary to refer particularly to the manner in which shoes and gaiters are now made.

Ladies' gaiters are either made open on the sides and laced up, the material of which the shoe is made being split down the side, with holes on each side of the opening for the strings, or they are made open on top, and a piece of the same material of which the gaiter is made, is sewed to one of the quarters of the gaiter, and made to button over on the other quarter, in order to cover the instep. This latter mode dispenses with strings but it is objectionable, because if it fits neatly, it is exceedingly difficult to button, and if the feet swell at all, which with many persons frequently occurs, they cannot button them at all, and this results from their covering the instep, or placing the fastenings for the gaiter to the same material of which the shoe or gaiter is made, which is not sufficiently elastic. Besides if the shoe is made of soft calf skin or kid, the button holes soon stretch from use, and become very unsightly, and this often when the shoes are but little worn. Shoes are also often split down on top over the instep, and the sides drawn together with strings, or the quarters of shoes are tied over the instep.

It is apparent to all persons of observation that shoe strings are a source of great annoyance. However carefully tied, they are liable to become untied, and present a slovenly appearance. They get into hard knots, which it is difficult to untie, and readily wear out. And these objections, though apparently trifling, cause daily the sale of a large number of boots, at more than twice the cost of shoes, for no other reason than the annoyance of shoe strings. I have seen so many persons made to buy boots from this consideration of getting rid of strings, that it would be a great gain to dispense with them.

I am aware that many attempts have been made to secure shoes to the feet without

strings and to some extent have been introduced into use. But where buckles and buttons have been used the points of fastening have always as far as I know been made of the same material with the shoe or gaiter, that is if the shoe be made of leather the buttons are sewed to the leather on one side, and the button holes worked in the leather on the other side, which is objectionable for many reasons, and cannot be made to answer as well as they would if the points of fastening were more elastic than the leather or lasting of which the shoe is made.

The use of boots has been superseded to a greater extent by Congress gaiters than by any other invention before the public. These dispense with shoe strings, and to this cause chiefly it is due that they are so much worn, not from any great degree of comfort they impart to the wearer. But they have no strings, and are cheaper than boots, hence their popularity. In these gaiters, elastic rubber cloth gores are inserted on each side, and stitched to the leather of which the gaiter is made. A gaiter thus made is formed to fit the ankle tight, and it must do this because in putting on the gaiter, the rubber gores on each side are greatly stretched, far more so than they are when the gaiter is on the foot, indeed when the gaiter is on the foot, it should fit the ankle snugly, without the rubber being stretched at all, and if the Congress gaiter could be gotten on the foot without the great stretching of the gores described, then it would be perfect and no improvement could be made upon it. But the necessity for this great stretching of the rubber gores in order to get on the gaiter, renders it necessary to make the gaiter fit the ankle tight; so that at first they bind the ankle uncomfortably and often so much as to be painful. The stretching of the gores relieves this after a time for they lose in part their elasticity and become permanently enlarged, but in doing this, the gaiter has lost its shape, and no longer fits close around the ankle. So also in order to dispense with strings, shoes have been made by inserting a piece of rubber over the instep, stitched all around to the leather. But here the same objection applies as to the Congress gaiter. From constant stretching in getting the shoe on and off, the rubber cloth loses in part its elasticity, ceases to bind across the instep sufficiently, and the shoe feels to the wearer as when untied.

To remedy these defects and at the same time dispense with strings, I insert in my shoes or gaiters, at the points where they are to be fastened, pieces of elastic rubber cloth, which are not sewed on to the leather all around as in the Congress gaiter, or the shoe described with the rubber stitched in over the instep, but it is sewed to the leather only on one side, for instance, if the gaiter be split down the side as they are now when they are fastened by lacing, I insert a piece of rubber cloth and sew it to one side of the slit opening, and lap it slightly on the other to be secured with hooks and eyes or small buttons, or you may insert the rubber on each side of the opening, and let it meet or lap in the center to be secured, the object being to use the elasticity of the rubber for the greater facility of fastening the gaiter whether by hooks and eyes, or by buttons. In a gaiter so constructed, if the foot swells, the rubber accommodates it; yet in putting on the gaiter, the rubber is not at all stretched but when the gaiter is on the foot, the elasticity of the rubber cloth increases the facility of fastening it, and just binds sufficiently to keep secured the hooks and eyes or buttons or fastenings used. There being no occasion for much stretching of the rubber cloth only enough to aid in fastening the gaiter, it will not permanently yield or get out of shape. It has therefore the advantages which the Congress gaiter has, if it could be gotten on without stretching the gores. The same principle is applicable to all shoes and gaiters however made; it is to attach to the shoe or gaiter at the points of fastening, elastic rubber cloth, either on both sides, when a portion of the fastenings would be attached to each piece of rubber, or on one side when a part of the fastening

would be attached to the rubber, and the corresponding part to the leather or material of which the shoes are made. Thus the hooks would be placed on one side and the eyes on the other or the buttons on one side, and the corresponding holes on the other.

Figure 1, represents two gaiters split down the sides, as they now are when secured by lacing. A, represents one in which the rubber is inserted on each side of the opening, and the fastenings are attached to each piece of rubber. B, represents the same form of gaiter where a single piece of rubber is inserted and the fastenings are attached to the rubber and to the material of which the gaiter is made.

Fig. 2, represents a gaiter buttoning over the instep with the rubber covering the instep sewed to the leather on one side, and buttoned to it on the other.

Fig. 3, represents a split down over the instep with the rubber inserted on each side of the opening, and secured in the middle.

I do not propose any change in the form of the shoes or gaiters as generally made, nor do I claim fastening the same with hooks and eyes or buttons or buckles, for this does not constitute my invention, but

What I claim and desire to secure by Letters Patent is,

Inserting in the shoe or gaiter at the points where it is to be fastened, a piece or pieces of elastic rubber cloth for the purpose of fastening the shoe or gaiter with hooks and eyes or buttons or buckles, substantially as described and thereby dispensing with shoe strings.

ALEXANDER HAY.
